[57] CLAIM

The ornamental design for a lid holder, as shown and described.

DESCRIPTION

FIG. 1 is a perspective view of a lid holder showing my new design;

FIG. 2 is a side elevation view thereof, the opposite side being a mirror image;

FIG. 3 is a rear elevation view thereof;

FIG. 4 is a front elevation view thereof;

FIG. 5 is a top plan view thereof;

FIG. 6 is a bottom plan view thereof;

FIG. 7 is a top plan view of an alternate embodiment of FIG. 1;

FIG. 8 is a bottom plan view of FIG. 7;

FIG. 9 is a side elevation view of FIG. 7, the opposite side being a mirror image;

FIG. 10 is a rear elevation view of FIG. 7;

FIG. 11 is a front elevation view of an alternate embodiment of FIG. 1;

FIG. 12 is a top plan view of FIG. 11;

FIG. 13 is a bottom plan view of FIG. 11;

FIG. 14 is a side elevation view of FIG. 11;

FIG. 15 is a rear elevation view of FIG. 11;

FIG. 16 is a front elevation view of FIG. 11;

FIG. 17 is a top plan view of an alternate embodiment of FIG. 1;

FIG. 18 is a bottom plan view of FIG. 17;

FIG. 19 is a side elevation view of FIG. 17, the opposite side being a mirror image;

FIG. 20 is a rear elevation view of FIG. 17; and,

FIG. 21 is a front elevation view of FIG. 17.
